UNITED STATES PATENT OFFICE.

EUGÈNE BUSWELL, OF WATERLOO, IOWA, ASSIGNOR TO THOMAS CASCADEN, JR., OF WATERLOO, IOWA.

FERTILIZER-DISTRIBUTER.

No. 928,024.

Specification of Letters Patent. Patented July 13, 1909.

Application filed August 21, 1908. Serial No. 449,698.

To all whom it may concern:

Be it known that I, EUGÈNE BUSWELL, a citizen of the United States of America, and a resident of Waterloo, Blackhawk county, Iowa, have invented certain new and useful Improvements in Fertilizer-Distributors, of which the following is a specification.

My invention relates to improvements in fertilizer distributers, and the objects of my improvements are these: First, to provide suitable mechanism for returning the conveyer-apron to its initial position when it has arrived at its limit of discharging movement; second, to furnish means for horizontally adjusting the spacing apart of the driven gear on the ends of the transverse operating-shaft in order to accommodate the distributor-mechanism to any one of various widths of wagon-boxes or running-gear; third, to supply automatic means for stopping the movement of the conveyer-apron when it has arrived at the limit of its discharging movement; fourth, to use suitable adjustable means for tightening up the conveyer-apron; and fifth, to variously adapt said improvements to be conveniently used in connection with special mechanism adapted to discharge the load at the forward part of the machine. These objects I have achieved by the mechanism and means which are hereinafter fully described and claimed, and which are illustrated in the accompanying drawings, in which;

Figure 1 is a right-hand side elevation or diagram of a fertilizer distributer equipped with my said improvements. Fig. 2 is a left-hand side elevation of the same. Fig. 3 is an enlarged detail of the shifting-mechanism for the slide-clutch on the right-hand end of the transverse operating-shaft. Fig. 4 represents enlarged details of the adjusting-means on the right-hand end of the operating-shaft with the various sprocket-wheels driven by said shaft. Fig. 5 is a side elevation of the conveyer-apron adjustable tightening-means. Fig. 6 is a perspective of one of the supporting brackets for said tightening means. Fig. 7 is a plan view of the forward end of the shifting arm for the said slide-clutch. Fig. 8 is a side elevation of the part depicted in Fig. 7. Fig. 9 is a plan view of the rack-bar bracket for the hand-lever used in connection with the mechanism for varying the degree of speed of the conveyer-apron. Fig. 10 is a perspec-

tive of the adjustable bracket-hanger for each end of the operating-shaft, and Fig. 11 is a side view of the part shown in Fig. 10 with supports. Fig. 12 is an enlarged side elevation of the driving-mechanism for the apron.

Similar numerals refer to similar parts throughout the several views.

The wagon-box 34 is connected to and supported by the parallel longitudinal side-beams 11. The said beams rest on bolsters, which in turn are supported by the front and rear axles of the front and rear carrying-wheels 107 and 39 respectively. The forward part of the frame of the box 34 is undercut to allow of the clearance of the front-wheels 107 in moving thereunder in turning the vehicle about. The rear end of the box is closed, while a distributor-drum 18 is secured to a transverse rotatable shaft 75 65 70 75 80 85 90 95 100 105 110

20 25 30 35 40 45 50 55 60 65 70 75 80 85 90 95 100 105 110

20 25 30 35 40 45 50 55 60 65 70 75 80 85 90 95 100 105 110

The box 34 contains a movable conveyer-apron, composed of transverse parallel slats 38 secured at each end to parallel longitudinal endless sprocket-chains 111. The chains are carried under the rear end of the box on sprocket-idlers 36 mounted on the ends of a transverse rotatable shaft 35, the ends of the latter being mounted in bearings 94 on the rear ends of adjustable bracket-plates 37. Each plate 37 is secured to the wagon-box by a bolt passed through the wagon-box, then through a spacing-block 91, then through said plate and secured by a nut 95. The bolt 92 referred to passes through the plate 37 by way of a longitudinal slot 96, the latter permitting longitudinal adjustment of the plate along the block. The forward end of the plate 37 has a flange 108, with a notched seat 97 in the upper edge of the latter for a horizontal bolt 90, the rear end of the latter being threaded to receive a nut 93, and said bolt being passed through a horizontal orifice in the block 91. By this means the shaft 35 is supported, and the latter may be shifted longitudinally by turning the bolt 90, when it is desired to tighten the conveyer-chains 111. The forward ends of the chains 111 are passed over 110

sprocket-wheels 22 secured to the ends of a rotatable transverse shaft 23.

The distributing-drum 18 and the movable conveyer-chains 111 are driven in the following manner: To the inner faces of the spokes of the rear carrying-wheels 39 are secured the driving sprocket-wheels 32. A transverse rotatable shaft 29 is mounted under the wagon-box a little in advance of the rear carrying-wheels in bearings 79 on each side of the machine, said bearings being the same as that shown in Fig. 4, and being laterally adjustable on the hangers 33. Each bearing-box 79 referred to, has projecting flanged members containing transverse vertical slots 78, the latter provided for adjustment, when the bolts 77 extending into said slots from the hanger 33 are loosened. When each bearing-box 79 has been adjusted to a certain position, it is restrained from inward movement by the slideable collar 74, the latter being secured to the shaft 29 by a set-screw 75. Just outside of each bearing-box 79 a compression spring is coiled about the shaft 29, and bearing against the outer end of each spring 98 is a sprocket-wheel 67 the outer end of whose hub has ratchet-teeth adapted to engage and coact with other ratchet-teeth on the inner ends of the sleeves 80 on said shaft. Both the sleeves 80 and the sprocket-wheels 67 are slideable along said shaft to adjust them apart in distance therealong, and when adjusted the sleeves are secured to the shaft by means of set-screws 81. The springs 98 then keep the ratchet-teeth aforesaid in coacting contact.

The hangers 33, which support the bearing-boxes 79, are made longitudinally adjustable in the following manner, to permit of keeping the chains which run over the sprocket-wheels 67 taut. The numeral 113 designates spaced apart parallel transverse beams secured to the under side of the box 34, by means of the bolts 112 which enter the longitudinal slots 76 in the hangers and which are secured thereto by nuts. The slots 76 permit of sliding of the hangers longitudinally over said bolts, when the bolts 104 whose heads engage grooves 105 in the flanged rear ends of the said hangers are moved longitudinally, as is shown in Fig. 11.

The shaft 29 is rotated by means of a sprocket-chain 31 on the left-hand side of the machine coacting with and engaging both of the sprocket-wheels 32 and 67 on that side. Power is communicated from the shaft 29 to the distributing-drum 18 and to the conveyer-apron 33 in the following manner. A sprocket-wheel 30 is both rotatably and slidably mounted on the right-hand end of the shaft 29, with ratchet-teeth on the left-hand end of its hub adapted to engage and coact with similar teeth on the right-hand end of the sleeve 80, when said wheel

30 is slid into engagement with said sleeve by means of the lever 17. The lever 17 has a fork 28 engaging an annular groove 68 in the right-hand end of the hub of the sprocket-wheel 30. A bracket 103 is secured to the right-hand side of the wagon-box 34, and has separated lugs 109 orificed in line to receive the pintles 40 projecting from a lug 110 secured to a medial part of said lever 17. The lever 17 is upwardly inclined 75 and has its forward end provided with a horizontal extension 86 having a vertical slot or slideway 88 to receive a slide-pin 87 which projects downwardly from a crank on a vertical rock-shaft 15, the latter rock-ing in the bearings 66. The upper end of said rock-shaft has a crank to which the rear end of a connection-rod 7 is pivotally connected by means of a bolt 14. The forward end of said connecting-rod is pivoted 85 at 6 to the lower end of a hand-lever 2, the latter being medially pivoted to a stud 5 on said wagon-box, and adapted to work in and adjustably engage a rack-bar 4 on said box. The hub 84 of a sprocket-wheel 19 is 90 adjustably secured to the right-hand end of the distributing-drum shaft 20 by means of a set-screw 85. A sprocket-chain 27 operatively connects the sprocket-wheels 30 and 19.

The forward conveyer-apron shaft 23 has on its right-hand end a driven-sprocket wheel 22 and on its left-hand end a ratchet-wheel 63. Said ratchet-wheel is driven from the distributing-drum shaft 20 by the following means. 58 is a disk secured to said shaft 20 and has a crank-pin 59 to which are pivoted the forward ends of the pitmen 49 and 62. The rear end of the pitman 62 is pivoted also to the driving-pawl 50 which 105 is pivoted on a stud extending from the lower end of a lever 51 whose upper end is pivoted to the box 34. The rear end of the pitman 49 is pivoted at 55 to the upper end of a lever 116, the latter being medially 110 pivoted on a stud 56 and having a driving-pawl 52 pivoted to its lower end on a stud 57. The pawls 50 and 52 engage and are adapted to drive the ratchet-wheel 63, moving alternately forward as separately actuated by the pitmen and levers above described, when the shaft 20 is rotated.

When it is desired to either vary the speed of the conveyer-apron or to disconnect the driving-pawls from the said ratchet-wheel 63, use is made of the following means: The lever 61, whose lower end is pivoted on the outer end of the shaft 23, has inturned members 114 and 115 which project inwardly over the teeth of the ratchet-wheel 63 under 120 the driving-pawls 50 and 52 respectively. A hand-lever 41 has its lower end fulcrumed on a stud 47, and works within a rack 42, its catch 99 adapted to be engaged between any of the teeth 100 of said rack. A rod 46 is 130

pivottally connected at 45 to said lever 41, and at its rear end to said lever 61. The hand-lever 41 may be shifted an appropriate distance forward or back to cause the members 114 and 115 to contact with and lift to a desired degree the driving-pawls 50 and 52 so as to correspondingly vary the length of their driving stroke on the ratchet-wheel. When the members 114 and 115 are moved forward to the limit they lift the pawls away from the teeth of the ratchet-wheel, which causes the latter to come to a stop.

The driving-pawls aforesaid may be caused to become disengaged automatically from the teeth of the ratchet-wheel by the following means, when the pusher 16 of the conveyer-apron 38 has arrived at the forward limit of its course. A slideway 48 is attached to an upright 13 secured to the left-hand side of the wagon-box. A slide-bar 44, whose forward end is pivoted to the hand-lever 41 at 43 is adapted to slide horizontally through said slideway. The rear free end of said slide-bar has a slot 117 through which a bolt 53 is inserted and secured through a slide-head 54. By this means the length of said slide-bar may be varied to a desired adjustment. The numeral 65 designates a contact-arm which projects laterally from the pusher 16, the latter being connected to the conveyer-apron 38, and has its outer end without the box bent downward so as to enter the plane of movement of the slide-bar 44. When the conveyer-apron 38 has moved forward to the end of its forward course, the projection 65 has contacted with and pushed forward the slide-bar 44 with the hand-lever 41, the connecting-rod 46 and the lever 61, and so caused the members 114 and 115 to lift the driving-pawls and stop the movement of the ratchet-wheel and the apron. In moving forward, the catch 99 of the lever 41 clicks over the teeth 100 of the rack 42, and becomes seated between such teeth at the end of stroke, thus holding the pawls away from the ratchet-wheel. I have adopted a device for moving back the conveyer-apron as follows. A bell-crank lever 21 is fulcrumed on the right-hand end of the shaft 23. The forward member of said lever is pivoted at 102 to the rear end of a connecting-rod 9 whose forward end is likewise pivoted at 10 to a lever 8. The lever 8 is pivoted at its lower end on a stud 12 projecting from the frame 11, and has a pedal at its upper end for the use of the operator.

The rear member of the bell-crank lever 21 has a longitudinal slideway 73 adapted to receive an adjustable slide 70, the latter being slotted at 71 to receive a bolt 72 extending from said rear member. The slide 70 has a transverse bearing-orifice in which is seated a laterally-adjustable pivot-shaft 25, and the latter is secured to said slide by a set-screw 82. A hub 161 carrying separated

sprocket-wheels 69 and 26 is rotatably mounted on said shaft 25, and a sprocket-chain 24 operatively connects the sprockets 69 and 22. The sprocket-wheel 26 lies in the plane of the sprocket-chain 17 and below it, and may be shifted upward into operative engagement with said chain 17, when the lever 8 is thrust forward. When the foot of the operator is removed from the pedal of the lever 8, the weight of the mechanism 75 connected to the rear member of the lever 21 will cause the sprocket-wheel to become disconnected from the chain 17, thus stopping the rearward movement of the conveyer-apron. The operator, when a fresh load in the box is ready to be distributed, may throw backward the hand-lever 41, which will cause the members 114 and 115 to drop from beneath the pawls 50 and 52, and the rotating shaft 20 will then cause the ratchet-wheel to be driven with the conveyer-apron 85 forward.

The hand-lever 2, which is pivoted to the box at 5 and works in the rack 4, is also pivottally connected at 6 to the forward end 90 of the connecting-rod 7, whose rear end is pivoted at 14 to the crank on the rock-shaft 15, and when said hand-lever 2 is shifted forward, the rock-shaft is turned to throw inward the upper end of the lever 17, which 95 causes the latter's fork 28 to move the hub 68 outward and thus disengage the teeth of said hub from the teeth on the outer face of the sleeve 80. The sprocket-wheel 30 then becomes idle on the shaft 29, and the rotation of the distributing-drum 18 and the movement of the apron are stopped. When the lever 2 is thrown backward, the above described process is reversed, and the drum 18 again set in rotation.

The adjustability of the sprocket-wheels on the shafts 29, 25, 23 and 20 as shown, laterally, permits of the use of the mechanism with boxes of different widths, or carrying-wheels differently spaced apart.

The forward part of the wagon-box is closed by a rearwardly-projecting screen 3 to protect the driver's seat 1 from material thrown to the front by the distributing-drum 18.

Having described my invention, what I claim as new, and desire to secure by Letters Patent, is:

1. In a fertilizer distributer, in combination, a receptacle mounted for transportation, a movable apron therein operatively connected to an endless chain, an endless chain, means for driving said chain, an idler for carrying one end of said chain, a horizontal bracket bearing for said idler, said bracket having a vertical longitudinal slot and a flange at one end with a notched upper edge, an orificed hanger depending from said receptacle, securing means for said bracket, hanger and receptacle extending through the

115

110

120

125

130

longitudinal slot of the bracket, and adjustable securing means seated in the notch of said bracket and in an orifice of said hanger, adapted to adjust the said bracket and bearing longitudinally along said receptacle to take up the slackness of said chain.

2. In a fertilizer-distributer, in combination, a wagon-box mounted on carrying-wheels, a rotatable shaft, a sprocket-wheel on said shaft, a sprocket-chain operatively connecting said sprocket-wheels, a movable conveyer-apron in said wagon-box, a rotatable apron-shaft having operative connections with said apron for moving it through said box, a second sprocket-wheel on the first-mentioned shaft, a distributing-drum mounted on a rotatable shaft at one end of said conveyer-apron, a sprocket-wheel on the end of the distributing drum shaft, a sprocket-chain operatively connecting the said second sprocket-wheel on the first-mentioned shaft and the sprocket-wheel on the distributing-drum shaft, a sprocket-wheel on one end of said apron-shaft, a bell-crank lever fulerumed on said apron-shaft, two connected sprocket-wheels rotatably mounted on one member of said bell-crank lever, a sprocket-chain connecting the sprocket-wheel on the apron-shaft with one of the sprocket-wheels on the bell-crank lever, and means for shifting the bell-crank lever to cause other sprocket-wheel thereon to operatively engage with the sprocket-chain connected to the sprocket-wheel on the distributing-drum shaft.

3. In a fertilizer distributer, in combination, a wagon-box mounted on carrying-wheels, a rotatable shaft, longitudinally-adjustable bracket-hangers supported by said wagon-box, laterally-adjustable bearing-boxes connected to and supported by said hangers, rotatable slidable sprocket wheels on said shaft provided with ratchet-teeth on the outer ends of their hubs, compression-springs between and engaging the said sprocket-wheels and their said adjacent bearing-boxes, laterally-adjustable sleeves removably secured on the ends of said shaft, said sleeves having ratchet-teeth on their inner ends adapted to engage the teeth on the outer ends of said sprocket-wheels, driving-sprocket wheels secured to one pair of said carrying-wheels, sprocket-chains operatively connecting said driving-sprocket wheels with the adjacent sprocket-wheels on said shaft, a sprocket-wheel connected to one of said sleeves and rotatable therewith, a distributing-drum mounted on a rotatable shaft, and a sprocket-chain operatively connecting the last-mentioned sprocket-wheel with a sprocket-wheel mounted on the distributing-drum shaft.

4. In a fertilizer distributer, in combination, a wagon-box mounted on carrying-wheels, a driving sprocket-wheel, a rotatable shaft, a sprocket-wheel on said shaft, a sprocket-chain operatively connecting said sprocket-wheels, a movable conveyer-apron in said wagon-box, a rotatable apron-shaft having operative connections with said apron for moving it through said box, a second sprocket-wheel on the first-mentioned shaft, a distributing-drum mounted on a rotatable shaft at one end of said conveyer-apron, a sprocket-wheel on the end of the distributing drum shaft, a sprocket-chain operatively connecting the said second sprocket-wheel on the first-mentioned shaft and the sprocket-wheel on the distributing-drum shaft, a sprocket-wheel on one end of said apron-shaft, a bell-crank lever fulerumed on said apron-shaft, two connected sprocket-wheels rotatably mounted on one member of said bell-crank lever, a sprocket-chain connecting the sprocket-wheel on the apron-shaft with one of the sprocket-wheels on the bell-crank lever, and means for shifting the bell-crank lever to cause other sprocket-wheel thereon to operatively engage with the sprocket-chain connected to the sprocket-wheel on the distributing-drum shaft.

5. In a fertilizer distributer, in combination, a wagon-box mounted on carrying-wheels, a driving sprocket-wheel, a rotatable shaft, a sprocket-wheel on said shaft, a sprocket-chain operatively connecting said sprocket-wheels, a movable conveyer-apron in said wagon-box, a rotatable apron-shaft having operative connections with said apron for moving it through said box, a second sprocket-wheel on the first-mentioned shaft, a distributing-drum mounted on a rotatable shaft at one end of said conveyer-apron, a sprocket-wheel on said distributing-drum shaft, a sprocket-chain operatively connecting the said second sprocket-wheel on the first-mentioned shaft and the sprocket-wheel on the distributing-drum shaft, a sprocket-wheel on one end of said apron-shaft, a lever fulerumed on said apron-shaft, two connected sprocket-wheels rotatably mounted on said lever, means for adjusting the position of said connected wheels along said lever, a sprocket-chain connecting the sprocket-wheel on the apron-shaft with the inner sprocket-wheel mounted on said lever, and means for moving said lever to operatively engage or disengage the outer wheel mounted on said lever with or from the sprocket-chain adapted to drive the sprocket-wheel on the distributing-drum shaft.

6. In a fertilizer distributer, in combination, a wagon-box mounted on carrying-wheels, a driving sprocket-wheel, a rotatable shaft, a sprocket-wheel on said shaft, a sprocket-chain operatively connecting said sprocket-wheels, a movable conveyer-apron

in said wagon-box, a rotatable apron-shaft having operative connections with said apron for moving it through said box, a second sprocket-wheel slideable on the first mentioned shaft and having means of engagement with said shaft, means for engaging or disengaging said second sprocket-wheel with or from said shaft, a distributing-drum mounted on a rotatable shaft at one end of said 10 conveyer-apron, a sprocket-wheel on one end of said distributing-drum shaft, a sprocket-chain operatively connecting the said second sprocket-wheel on the first-mentioned shaft and the sprocket-wheel on the distributing- 15 drum shaft, a sprocket-wheel on one end of said apron-shaft, a lever fulcrumed on said

apron-shaft, two connected sprocket-wheels rotatably mounted on said lever, a sprocket-chain connecting the sprocket-wheel on the apron-shaft with one of the sprocket-wheels 20 on said lever, and means for moving said lever to cause the other sprocket-wheel thereon to operatively engage with the sprocket-chain which drives the distributing-drum. 25

Signed at Waterloo, Iowa, this 5th day of August, 1908.

EUGENE BUSWELL.
